UNITED STATES PATENT OFFICE

FREDRIK W. HVOSLEF, OF DEARBORN, MICHIGAN, ASSIGNOR TO THE TIMKEN SILENT AUTOMATIC COMPANY, OF DETROIT, MICHIGAN, A CORPORATION OF MICHIGAN

OIL BURNER

Application filed December 27, 1928. Serial No. 328,689.

My invention relates to oil burners and has for its principal object a burner that is simple and compact in construction, that provides a thoroughly atomized fuel and an adequate supply of air to support the combustion thereof, that regulates the flow of air so as to prevent excessive whirling and eddying thereof and that simply and effectively takes care of any leakage of oil from the atomizing pump. The invention consists principally in the oil burner, in the device for preventing leakage of fuel from the atomizing pump and in the parts and combinations and arrangements of parts herein-
10 after described and claimed.

15 In the accompanying drawings,

Fig. 1 is a part side elevation, part sectional view of an oil burner embodying my invention,

20 Fig. 2 is a top plan view, a portion of the casing being broken away, and

Fig. 3 is a cross-sectional view on the line 3—3 in Fig. 1.

25 A housing 1 has a nosing 2 secured to the front end thereof as by screws 3. Spaced away from the rear end of the housing 1 by lugs 4 and secured thereto as by screws 5 is an end wall member 6, two mounting legs 7 being secured to said end wall member and a
30 third 8 to said nosing. Secured to said rear end of said housing 1 as by screws 9 and forced away therefrom by means of coil springs 10 on said screws is a cover plate 11. By adjusting the distance of said cover plate
35 11 from the end of the housing 1, the amount of air entering the housing may be regulated.

The interior of the housing 1 is provided with a plurality (six being the preferred number) of equiangularly spaced radial fins
40 12 that extend lengthwise of the housing and support at their inner front end portions an annular member 13 having at its center a tubular bearing portion 14 through which extends a shaft 15. The rear end portion 16 of said tubular bearing member 14 itself constitutes the bearing for the rear end of said shaft 15 and a suitable bushing 17 is provided for the forward end of said shaft 15. A packing 18 is provided for the body
45 portion of said shaft and said bushing 17 has

a groove 19 in its upper surface that communicates with a radial passageway 20 through said annular member 13, whereby lubricant may be supplied for said packing
18.

50 Mounted on the forward end of said shaft 15 is a pump rotor 21, the pump body 22 being mounted against the forward face of said annular member 13 and the pump cover 23 being secured to said pump body 22.

The pump cover 23 is provided with a projecting stem 24 that has a longitudinal bore 25 communicating with a transverse bore 26 in said cover which has a small longitudinal bore 27 at its end communicating with the interior of the pump body 22; so that atomized fuel leaving the pump traverses a substantially Z-shaped path. The end of said projecting stem 24 is threaded and a burner tip or nozzle 28 is screwed thereon. Secured to said projecting stem 24 as by a set screw 29 is a conical shell 30 that projects beyond the end of the nozzle 28 and is provided with a plurality of slotted openings 31 about in line with the end of said nozzle. A spark plug 32 for igniting fuel is secured to said nosing 2 and its points 33 project into the interior thereof a little in front of said conical burner shield 30.

55 Rigidly mounted on said bearing member 14 is the armature 34 of an electric motor whose rotary field 35 is secured to a support 36 that is mounted on the rear end of said shaft 15, said rear end of said shaft and the bore of said support being tapered so that
60 the two may be firmly secured together by means of a nut 37 on the end of the shaft.

Secured to the field support 36 as by screws 38 are fan blades 39 that force air through the housing and into the nosing. The outside diameter of said fan is slightly less than the inside diameter of said housing and the fan is disposed adjacent to the rear ends of said fins 12. The air from the fan would normally have a whirling motion which would interfere with combustion, but the radial fins prevent this whirling motion of the air and cause it to flow straight through the housing 1 and nosing 2. The conical shield 30 in which
65 100

the nozzle is disposed protects the flame from excessive air currents.

Fuel oil is supplied to the atomizing pump by means of a supply line including a magnetic valve 40 of suitable construction and a feed pipe 41 that terminates in an opening in the pump body 22. Air enters the pump through a separate air passageway 42 disposed substantially radially of said annular member 13 and having a short cross port 43 communicating therewith and opening into the interior of the pump body. Thus the air and oil are separate until they reach the interior of the pump. The interior of said bushing 17 is provided with an annular groove 44 near its forward end and said air passageway 42 in said annular member is extended beyond the cross port to communicate with said groove 44. Thus if any oil should escape from the pump it would enter said groove 44 and by reason of the suction of the pump would pass back through said air passageway 42 and said cross port 43 into the body of the pump.

25 Any suitable electric control set may be provided for the motor and for the spark plug, the drawings showing diagrammatically a control box 45 and a transformer box 46 for the spark plug.

30 The above described oil burner has numerous advantages. The motor, fan and pump are all enclosed in a housing which protects them from injury and from unnecessary tampering, the motor is cooled by the passage 35 of air thereover, the air fan and fuel pump balance each other, the compact arrangement makes for simplicity and inexpensive construction, the short motor shaft eliminates the necessity for universal joints, leakage of 40 fuel oil from the pump is prevented by simple and effective means and the burner is very quiet and is economical in operation. Obviously numerous changes might be made without departing from the invention and I 45 do not wish to be limited to the precise construction shown.

What I claim is:

1. An oil burner comprising a housing including a nosing portion and having an air 50 opening at the rear end thereof, an annular mounting member disposed centrally of said housing, fins in said housing extending lengthwise thereof and supporting said mounting member, a tubular bearing member 55 extending lengthwise of the housing and supported by said annular mounting member, a shaft extending through said bearing member, a pump rotor on the forward end of said shaft, a pump body secured to said mounting 60 member, a pump cover secured to said body and having a fuel passageway opening into the interior of said pump body, a burner nozzle secured to said pump cover and communicating with said fuel passageway thereof, means for supplying oil and air to the 65

interior of said pump body, a fan at the rear end of said shaft and a motor between said fan and pump for rotating said shaft.

2. An oil burner comprising a housing including a nosing portion and having an air 70 opening at the rear end thereof, an annular mounting member disposed centrally of said housing, fins in said housing extending lengthwise thereof and supporting said mounting member, a tubular bearing member 75 extending lengthwise of the housing and supported by said annular mounting member, a shaft extending through said bearing member, a pump rotor on the forward end of said shaft, a pump body secured to said mounting member, a pump cover secured to said body and having a fuel passageway opening into the interior of said pump body, a burner nozzle secured to said pump cover, and communicating with said fuel passageway 80 thereof means for supplying oil and air to the interior of said pump body, a fan at the rear end of said shaft, a motor between said fan and pump for rotating said shaft, a conical shield member mounted on said pump cover over said burner nozzle and projecting beyond said burner nozzle and means in said nosing beyond the end of said conical shield member for igniting fuel.

3. An oil burner comprising a housing including a nosing portion and having an air opening at the rear end thereof, an annular mounting member disposed centrally of said housing, fins in said housing extending lengthwise thereof, and supporting said mounting member, a tubular bearing member 100 extending lengthwise of the housing and supported by said annular mounting member, a shaft extending through said bearing member, a pump rotor on the forward end of said shaft, a pump body secured to said mounting member, a pump cover secured to said body and having a fuel passageway opening into the interior of said pump body, a burner nozzle secured to said pump cover and communicating with said fuel passageway 105 thereof, means for supplying oil and air to the interior of said pump body, a fan at the rear end of said shaft, a motor between said fan and pump for rotating said shaft, a conical shield member mounted on said pump cover over said burner nozzle and projecting beyond said burner nozzle, said shield having holes therethrough about in line with the forward end of said burner nozzle and means in said nosing beyond the end of said conical shield member for igniting fuel.

4. An oil burner comprising a housing including a nosing portion and having an air 115 opening at the rear end thereof, an annular mounting member disposed centrally of said housing, a tubular bearing member extending lengthwise of the housing and supported by said annular mounting member, a shaft 120

extending through said bearing member, a pump rotor on the forward end of said shaft, a pump body secured to said mounting member, a pump cover secured to said body and

6 having a fuel passageway opening into the interior of said pump body, a burner nozzle secured to said pump cover and communicating with said fuel passageway thereof, an oil supply pipe opening into the interior of

10 said pump body, said annular mounting member having an air passageway therethrough opening into the interior of said pump body, a fan at the rear end of said shaft and a motor between said fan and pump

15 for rotating said shaft.

5. An oil burner comprising a housing including a nosing portion and having an air opening at the rear end thereof, a plurality of equiangularly spaced fins extending lengthwise of said housing, an annular mounting member disposed centrally of said housing and supported by said fins, a tubular bearing member extending lengthwise of the housing and supported by said annular mounting

20 member, a shaft extending through said bearing member, a pump rotor on the forward end of said shaft, a pump body secured to said mounting member, a pump cover secured to said body and having a fuel passageway opening into the interior of said pump body, a burner nozzle secured to said pump cover and communicating with said fuel passageway thereof, separate oil and air passageways leading to said pump body, a fan

25 at the rear end of said shaft, an electric motor armature fixed on said tubular bearing member, a rotary motor field mounted on a support having a beveled bore in which fits the tapered rear end portion of said shaft, a

30 nut for securing said field support to said shaft and fan blades secured to said field support.

Signed at Detroit, Michigan, this 20th day
of December, 1928.

45 FREDRIK W. HVOSLEF.
